UNITED STATES PATENT OFFICE.

CARL OSCAR ANDERSON, OF SPRINGFIELD, ILLINOIS, ASSIGNOR, BY MESNE ASSIGNMENTS, TO THORNE BROTHERS, INCORPORATED, OF CHICAGO, ILLINOIS, A CORPORATION OF ILLINOIS.

POWER DRIVE FOR CREAM SEPARATORS.

Application filed June 24, 1918. Serial No. 241,504.

To all whom it may concern:

Be it known that I, CARL OSCAR ANDERSON, a citizen of the United States, residing at Springfield, in the county of Sangamon and State of Illinois, have invented certain new and useful Improvements in Power Drives for Cream Separators, of which the following is a specification.

The invention has relation to driving mechanism for machines in which heavy 10 inertia must be overcome in starting and operating, and wherein slow initial movement is necessary, being primarily concerned with power drives for centrifugal machines, 15 such as cream separators and the like.

Machines of the character noted are frequently driven by explosive engines wherein the power is of pulsating character, so that the machines are subjected to knocks and 20 jerks in the engine, incidental to its power development, which injuriously affects the machine and likewise the operation of the latter in the work being performed. Particularly is this true in connection with 25 cream separators, wherein slow starting is not only necessary but where uniform application of power and maintenance of speed are also required. It is the object, therefore, 30 of the present invention to provide a power drive for these machines which will eliminate transmission of the pulsations of the prime mover to the driven machine, thus freeing the latter from the shocks inherent in the irregular power generation, and permitting 35 the driven machine to be operated under the uniform application of power and at such uniformity of speed as to insure the highest results in the operation of the driven machine.

40 The invention further aims to provide a power drive of the character stated which is of simplified construction and minimum parts, and in which the elements are so organized and related as to require minimum 45 repair and little attention to the operation of the drive.

Other objects and advantages of the invention will appear as the nature of the improvements is better understood, the invention 50 consisting substantially in the novel construction, combination and arrangement of parts hereinafter fully described, illustrated in the accompanying drawings, and

finally pointed out in the appended claims. It is to be understood, however, that the 55 present exemplification constitutes but one embodiment of the invention, and the same is to be considered only in an illustrative, and not in a restrictive sense.

In the drawings—

Fig. 1 is a top plan view of a power drive constructed in accordance with the present invention; and

Fig. 2 is a side elevation thereof.

Referring in detail to the accompanying 65 drawing, the numeral 10 designates the usual type of shelf which is designed to be inserted between the base and stool of a cream separator. This shelf is provided at one of its ends with a projection 11 constituting the support of the hereindescribed power drive. This projection is in the form of a plate formed integral with the shelf 10, and the end of said projection 11 which is remote from the shelf 10 is provided with 70 a pair of spaced perforated lugs 12 in which is mounted a shaft 13.

Mounted in the space between the lugs 12 is a swinging frame plate 14, said plate 14 having at one of its ends a pair of spaced 80 parallel perforated ears 15 which are angularly disposed with respect to the body of the plate 14, said ears 15 having oppositely disposed aligned bearing sleeves 16. The perforated ears 15 receive the shaft 13 and are 85 supported by the latter in the space between the lugs 12, thus providing for the swinging connection of the frame plate 14 with the supporting projection 11. Rotatably mounted in the sleeve 16 is a shaft 17 at one end of which 90 is mounted a driving pulley 18, while at the opposite end of said shaft 17 are arranged tight and loose pulleys 19 and 20, respectively. To the pulleys 19 and 20 is applied a power belt 21 which leads from a prime 95 mover, such as a gas engine or other form of motor. A driving belt 22 is trained over the driving pulley 18 and leads to a pulley 23 mounted on the shaft of the driven machine. When the pulley 23 is associated 100 with a cream separator, or similar centrifugal machine, the same is applied to the worm wheel shaft 24 of such machine.

The end of the frame plate 14 which is opposite to the ears 15 thereof is bifurcated, 105 as at 25, to provide a pair of spaced parallel

attaching lugs 26. These lugs are perforated to receive a pin 27, and fitted to said pin 27 between the lugs 26 is the perforated lower end of a tension rod 28. The tension rod 28 passes upwardly through a perforation in the supporting projection 11, so that the upper end of the rod 28 is disposed above the upper surface of said projection 11, and mounted on the upper end of the rod 28 so as to rest against the projection 11 is a washer 29 which forms a buffer for the lower end of a tension spring 30 the coils of which encircle the rod 28. The upper extremity of the latter is screw-threaded, as at 31, an adjusting nut 32 engaging the screw threads 31, and likewise the upper end of the spring 30, the nut 32 serving as a means for tensioning the spring 30 as adjustment of said tension may be necessary.

20 A belt shifter 33, of usual construction, is associated with the pulleys 19 and 20, the same being operated by a shifting bar 34 slidably mounted in supporting loops 35 arranged at the under face of the frame plate 14. A connecting stud 36 is carried by the bar 34 and fitted in a notch 37 formed in the short arm of a bell crank lever 38 which is pivotally mounted on the frame plate 14 by a bolt 39, or its equivalent. The long arm of the bell crank lever 38 projects at one side of the plate 14 to be conveniently grasped by the operator when it is desired to shift the belt 21 over the pulleys 19 and 20.

In the use of the herein described power drive, particularly when the same is employed with a cream separator, the same is positioned in operative relation to the machine when the shelf 10 is assembled with the base and stool thereof. The power belt 21 is applied to the pulleys 19 and 20, and the driving belt 22 likewise applied to the driving pulley 18 and the driven pulley 23, in the manner illustrated in Fig. 2, so that while power is derived from the prime mover, it is not a direct application of the power to the driven pulley 23, but it is through a yieldingly mounted transmitting element which takes up the shocks and jerks incidental to the pulsating character of the power developed in the gas engine. The tension of the spring is properly adjusted to impart the required tension to the driving belt 22, and the tight side thereof is thus held for transmitting the power to the driven pulley under the normal conditions of operation. If, however, the driving pulley 18 be subjected to a shock or jar from the prime mover so that the power transmitted through the belt 22 becomes greater than the tension in the spring 30, the spring becomes slightly compressed, under the pull of the tension rod 28 induced by the movement of the shaft 17 and the frame plate 14, thereby allowing the belt 22 to slip on the pulleys 18 and 23 to counteract the shock or jerk caused by the

pulsation of the motor, and eliminate the same from the driven pulley 23. The driven machine is thus protected, being driven under uniform conditions of power and speed, and not being injuriously affected by the 70 pulsations of the prime mover.

While the herein described invention has been referred to in connection with the operation of centrifugal machines, and particularly cream separators, it will be apparent 75 that the same is susceptible to use in other relations for driving purposes where it is desired to protect the driven machines from shocks and jars arising in the source of power, or the driving connections from 80 which the operation of the driven machine is derived. The invention, therefore, is not to be restricted to the specific sphere of utility herein set forth.

I claim:

1. In a power drive of the class described, the combination with a supporting element, of a driven pulley, a frame plate hingedly connected to said supporting element, a driving pulley carried by said frame plate, a belt connecting the driving and driven pulleys, a tension rod connected to said frame plate, and means associated with said tension rod and cooperating with said supporting element, whereby to place the driving 90 pulley normally under tension with respect to the driven pulley and hold the belt under tension, said tensioning means being susceptible to shock imposed on said driving pulley arising in its driving connection, whereby to slacken said belt and free the driven pulley from said shock.

2. A power drive of the class described, comprising a supporting plate, a frame plate hingedly connected thereto, a driving pulley carried by said hinged plate and movable thereby with respect to said supporting plate and also with respect to the elements driven by said driving pulley, and a tensioning device connected to said frame plate and operatively related to said supporting plate for holding the driving pulley under tension 110 with respect to the driven element.

3. In a power drive of the class described, the combination with the shelf of a cream separator, of a driving pulley, a support for said driving pulley hingedly connected to said shelf, and a tensioning device pivotally connected to said support and operatively related to said shelf for imparting tension 115 to said driving pulley with respect to the elements driven thereby.

4. In a power drive of the class described, the combination with the shelf of a cream separator, of a driving pulley, a frame plate 125 hingedly connected to said shelf, said frame plate serving as a yielding support for said driving pulley, and a tensioning device associated with said hinge plate and cooperating with said shelf for imparting tension 130

- to said driving pulley with respect to the elements driven thereby.
5. A power drive of the class described, comprising a support, a swinging member hingedly connected to said support and provided with aligned bearings, a driving shaft mounted in said bearings, a tensioning member connected to said swinging member, means associated with said tensioning member and yieldably engaging said support for maintaining the driving shaft in tensioned relation to the element driven thereby, and means for regulating said tensioning means.
10. A power drive of the class described, comprising a support, a swinging member hingedly connected to one end of said support and extending above and below the latter, the upper portion of said swinging member being provided with aligned bearings, a driving shaft mounted in said bearings, a tensioning member connected to the lower portion of said swinging member and extending above said support, tensioning means associated with said tensioning member and bearing against said support to maintain said driving shaft in tensioned relation to the element driven thereby, and means also carried by said tensioning member and cooperating with said tensioning means for regulating the degree of tension of the latter.
15. A power drive of the class described, comprising a support, a swinging member hingedly connected to one end of said support and extending above and below the latter, the upper end of said swinging member having aligned bearings, a driving shaft arranged in said bearings, a tensioning member extending through said support and having its lower end connected to the lower end of said swinging member, a tension spring surrounding the upper end of said tension member and having one of its ends yieldably engaging said support, and means carried by said tension member and cooperating with said spring for regulating the tension of the latter.
20. A power drive of the class described, comprising a support, a frame plate hingedly connected to one end of said support, the lower end of said frame plate being disposed at a point beneath said support, a driving shaft carried by said frame plate, a tension rod connected to the lower end of said frame plate and extending above said support, a tension spring carried by said tension member and bearing against said support, and means also carried by said tension member and co-operating with said spring for regulating the tension of the latter.
25. A power drive of the class described, comprising a support, a frame plate hingedly connected to one end of said support, the lower end of said frame plate being disposed below said support, a driving shaft carried by the upper end of said frame plate, tight and loose pulleys carried by said driving shaft, belt shifting means carried by said frame member and arranged in operative relation to said tight and loose pulleys, and tensioning means connected to the lower end of said frame plate and operatively related to said support for holding said driving shaft in tensioned relation to the element driven thereby.
30. A power drive of the class described, comprising a support, a swinging member hingedly connected to one end of said support, the lower end of said swinging member being disposed below said support, a driving shaft carried by the upper end of said frame member, tight and loose pulleys carried by said driving shaft, belt shifting means carried by said frame member and arranged in operative relation to said tight and loose pulleys, a tension rod hingedly connected to the lower end of said frame plate and extending above said support, a tension spring associated with said rod and bearing against said support, and means also carried by said rod for regulating the tension of said spring.
35. A power drive of the class described, comprising a support having a pair of perforated spaced lugs, a shaft mounted therein, a frame plate mounted on said shaft between said lugs for swinging in relation to said support, a driving shaft carried by said frame plate, the lower end of the latter extending below said support, a tension rod hingedly connected to the lower end of said frame plate and extending above said support, a tension spring associated with said

tension rod and bearing against said support, and means carried by said tension rod for regulating the tension of said spring.

14. A power drive of the class described, comprising a support having a pair of perforated spaced lugs, a shaft mounted therein, a frame plate mounted on said shaft between said lugs for swinging in relation to said support, a driving shaft carried by said frame plate, the lower end of the latter extending below said support, the tension rod hingedly connected to the lower end of said

frame plate and extending above said support, a tension spring surrounding said tension rod, a washer also carried by said tension rod and interposed between said spring and said shelf to form a buffer for said spring, and means also carried by said tension rod for regulating the tension of said spring. 15
